UNITED STATES PATENT OFFICE

WILLIAM JACOB KUNTZ, OF YORK, PENNSYLVANIA

BEATER MILL

Application filed April 18, 1928. Serial No. 270,986.

This invention relates to a beater mill.

An object of the invention is the provision of a beater mill having an automatic throw-out, through which are adapted to be ejected 5 the heavier particles while the fines from the particles are ejected through a separate path.

Another object of the invention is the provision of a beater mill in which a revolving beater is adapted to forcibly act upon heavier 10 particles from a hydrating plant for lime, and in which the heavier particles carry upon the surface, fines of hydrated lime which it is adapted to recover, the mill having a discharge passage through which the heavier 15 particles are ejected with means in the passage for controlling at will, the size of the particles ejected through the passage.

A further object of the invention is the provision of a beater mill in which a revolving 20 beater having a plurality of arms is revolved, and over a grate, through which the fines from heavier particles of lime are ejected, the heavy particles being subjected to considerable 25 force in the mill by the arms, for the purpose of removing fines which are eventually ejected through the grate, the heavier particles being discharged through a passage which is more or less restricted by pivotally 30 mounted vanes adjustable relative to each other, thereby controlling the size of the particles ejected through the last mentioned passage.

This invention will be best understood from a consideration of the following detailed 35 description in connection with the accompanying drawings; nevertheless, it is to be understood that the invention is not confined to the disclosure being susceptible of such changes and modifications as shall define no material departure from the salient features of 40 the invention as expressed in the appended claims.

In the drawings:

Figure 1 is a vertical section of the beater 45 mill constructed according to the principles of my invention,

Figure 2 is a side view in elevation of the same,

Figure 3 is a longitudinal vertical section 50 of the beater mill.

Referring more particularly to the drawings 10 designates a housing having side walls 11 and 12, and each side wall formed of sections 13 and 14. These sections are flanged and bolted to the end walls 15 and 16, and a 55 top 17. The bottom, as shown at 18, is open.

A feeding chute 19 is formed integral with the top 17 and rests upon the top of the end wall 16, as shown at 20. The side wall 13 is extended, as shown at 21, for closing the open 60 side of the chute 19. A feeding pipe 22 leads into the chute 21, and is connected with any suitable source of supply of heavy particles of lime which may be cores or unburned or unhydrated lime, which are coated with fine 65 particles of hydrated lime. It is these fine particles of hydrated lime which it is intended to recover in this mill, or in other words, the heavy particles which are covered with such fines are adapted to be agitated with considerable force in this mill for causing the fine particles to be removed from the heavy 70 particles, after which the fine particles are discharged from the mill in a separate path from the heavier particles.

A reinforcing plate 30 is secured to the inner face of the top 17 and is adapted to receive the heavy particles as they are thrown upwardly by the revolving beater arms 31. Plate 30 thus protects top 17 against undue 75 wear. A plurality of blocks 32, 33 and 34 are located in staggered relation in the upper corner of the housing 10, and receive the heavier particles as they are thrown upwardly 80 by the arms 31 after said particles are received from the chute 19. These blocks are not only supported in position respectively 85 by the screws 35, 36 and 37, but said screws are adapted to adjust these blocks towards 90 or away from the arms.

A curved inner liner 38 is located in contact with an upper portion of the end wall 15 and extends from the lower block 34 downwardly and terminates a curved grate 39, which is disposed adjacent the opening 18, 95 and over which the free ends of the arms move. The grate 39 consists of a plurality of V-shaped bars 40 with the portions of the bars of greater width than either adjacent the free ends 41 of the arms 31. The upper 100

enlarged portions of the bars are separated from each other, a slight distance, to provide passages 42 through which the fines are discharged.

- 5 The beater consists of a plurality of disks 43 having a plurality of circumferentially arranged passages to receive bolts 44, and which receive passages in the arms 31 for securing the arms to the disks. The arms 31 are 10 spaced a sufficient distance apart, and terminate at their inner ends a short distance from the shaft 45, and additional disks 46 which have substantially the same thickness as the arms 31 are located between the disks 43 and 15 have passages to receive the shaft 45. The disks 43 and 46 are keyed to said shaft, as shown at 47. Bolts 48 pass through perforations in the disks 46 and 43 for securing the plurality of disks together as a unit.
- 20 The side walls 11 and 12 which includes the sections 13 and 14 are provided with laterally disposed flanges 50 provided at their upper ends with a removable bearing 51 for supporting the ends of the shaft 45. A casing 25 60 is secured at 61 to the end wall 16 of the housing 10 and has an open end embracing an opening 62 formed in said end wall of the housing.

A casing 60 has an internal chamber 63 30 forming a discharge passage for the heavier particles which are ejected by means of the beater arms 31 from the housing 10. The lower end of the casing 60 has a discharge opening 64 which places the chamber 63 in 35 communication with a discharge spout 65. The gate valve 66 is hingedly mounted at 67 in the spout and is adapted to have its lower end 68 in snug contact with the adjacent wall of the spout whereby the open end of the 40 spout is substantially closed to the atmosphere.

A vane 70 is rigid with the shaft 71 which projects through the section 14 of the side wall of the housing and through which projection is rigidly secured an operating arm 72 whereby the vane 70 may be manually adjusted as will be presently described. The free end 73 of the vane 70 projects into a chamber 63.

45 A vane 75 is rigid with the shaft 76 and projects through the side wall of the casing 60, as shown at 77 and into which projection is connected an operating arm 78 whereby the vane 75 may be manually positioned. The free ends 79 of the vane extends toward the housing 10 and is normally located adjacent the opening 62. A third vane 80 secured to a 55 shaft 81 has its free end 82 sheared at an angle and in engagement with the end of the 60 vane 75 adjacent the shaft 72.

The operation of my device is as follows:

The ejected heavier particles from a hydrating plant are normally covered with fines of hydrated material which it is desired to 55 recover. While the heavier particles which

consist of unburned lime, cores, and lime which have not been properly hydrated, are conducted by means of the pipe 22 and the chute 21, into the mill, whence they are deposited upon the revolving beater and received by the arms 31. The revolving arms throw the heavy particles against the plate 30 and also against the blocks 32, 33 and 34 somewhat violently and with sufficient force to cause the thrown heavier particles to be relieved of the fines which consists of hydrated lime, and these fines are discharged through the passages 42 in the grate 39, after which they are collected.

70 The third vane 80 is adjusted by means of exteriorly disposed operating handle 90 so as to cause a circulation of air currents through the openings between the free ends 73 and 79, respectively, of vanes 70 and 75, and then through the chamber 63. The air currents pass upwardly in chamber 63 between the upper ends of the vane 75 and casing 60 and through the opening caused by the proper positioning of the vane 80. These air currents then pass on and into the air currents caused by the revolving arms 31. Air currents traveling in this cycle lift and carry the fine material and dust thereby causing the separation and preventing the fine material from passing out through the discharge openings 64.

75 The gate valve 66 may be positioned also and held in position by thumb screws (not shown) so as to form an opening between the free end 68 of the gate valve and the wall of the discharge spout 65, thereby allowing air currents to enter through the opening 64 passing through chamber 65 and upwardly between the rear end of vane 75 and casing 60. These currents then pass vane 80 and enter 80 the revolving currents in the housing of the beater mill preventing the escape of fine material or dust through the opening between the free end 68 and the walls of the discharge spout 65. The vane 70 is located in order to 85 form an angle of repose from the outer circle of the revolving material which is caused by the rotating beater arms 31. The larger and heavier materials are travelling in the outer circle of the fast travelling material by means 90 of centrifugal force. When the materials reach the vane 70 which projects away from this outer circle they are forced upwardly between vanes 70 and 75 into the chamber 63. The quantity and size of the material 95 leaving the revolving mass is definitely controlled by positioning vanes 70 at a greater or less angle to the vertical.

100 Vanes 75 may be positioned in order to cause the free ends 79 to project into the housing of the beater mill more or less so that the free ends will come into contact with the revolving mass of material to cause a larger or smaller material, as the case may be, 105 to pass off from the revolving mass into the 110

chamber 63, through the opening between the free ends of the vanes 70 and 75.

I claim:—

- 5 1. A beater mill comprising a housing, a beater mounted for rotation in said housing, a discharge chamber having an opening communicating with the housing through which particles are ejected from the housing by the beater, a plurality of vanes movable across the opening and adjustable relative to each other for controlling the size of the particles thrown into the discharge chamber, one of the vanes being located substantially in the housing and having a free end projecting into the discharge chamber.
- 10 2. A beater mill comprising a housing, a beater mounted for rotation in said housing, a discharge chamber having an opening communicating with the housing through which particles are ejected from the housing by the beater, a plurality of pivotally mounted vanes movable across the opening and adjustable relative to each other for controlling the size of the particles thrown into the discharge
- 15 25 chamber, the free ends of certain of the vanes being disposed adjacent each other, one vane extending from its pivot in a direction which is opposite to the direction of projection of a closely associated vane.
- 20 30 3. A beater mill comprising a housing, a beater mounted for rotation in said housing, a discharge chamber having an opening communicating with the housing through which particles are ejected from the housing by the beater, a plurality of vanes movable across the opening and adjustable relative to each other for controlling the size of the particles thrown into the discharge chamber, one of the vanes being located in the discharge
- 25 35 40 45 chamber and having the free end projecting toward the interior of the housing, another vane being located in the housing and having the free end projecting into the discharge chamber.

WILLIAM JACOB KUNTZ.
